UNITED STATES PATENT OFFICE

113,235

DESIGN FOR A COMBINED CARAFE, CUP, AND COASTER

John R. Morgan, Oak Park, Ill., assignor to Sears, Roebuck and Co., Chicago, Ill., a corporation
of New York

Application October 8, 1938, Serial No. 80,322

Term of patent 7 years

To all whom it may concern:

Be it known that I, John R. Morgan, a citizen of the Republic of Guatemala, residing at Oak Park, in the county of Cook and State of Illinois, have invented a new, original, and ornamental
Design for a Combined Carafe, Cup, and Coaster, of which the following is a specification, reference being had to the accompanying drawing, forming a part thereof.

Fig. 1 is a perspective view of a combined carafe, cup and coaster embodying my new design.

Fig. 2 is an elevational view thereof.

Fig. 3 is a top plan view thereof.

I claim:

The ornamental design for a combined carafe,
cup, and coaster, substantially as shown.

JOHN R. MORGAN.
